LIVE BAIT LURE

John R. Ditson, 1919 S. Ewing, Dallas, Tex.

Filed June 18, 1962, Ser. No. 70,581

Term of patent 14 years

(Cl. D31—4)

Fig. 1

Fig. 2

Fig. 3

FIG. 4.

FIGURE 1 is an elevational view of a live bait lure, embodying my new design.

FIGURE 2 is a top plan view thereof, and

FIGURE 3 is an inverted plan view thereof.

FIGURE 4 is a perspective view thereof.

The essential features of the design reside in the portions shown in full lines.

I claim:

The ornamental design for a live bait lure, substantially as shown and described.
